EYEGGLASS LENS MOUNTING

Robert Sumner, Los Angeles, Calif.

Application June 19, 1939, Serial No. 279,909

3 Claims. (Cl. 88—47)

This invention relates to a mounting for the lenses of eyeglasses of the rimless type and more particularly pertains to improvements in lens mountings of the character in which a resilient element is interposed between the margin of the lens and a shoe carrying lens engaging straps so as to impose a lateral yieldable thrust on a fastening screw passing through the lens and engaging the straps to hold the screw against unwanted loosening and at the same time afford a cushioned interconnection between the lens and its support such as to minimize breakage of the lens by reason of strains imposed thereon through the mounting. Various constructions have heretofore been devised for the purpose above stated, but because of the minuteness of the mounting and its parts considerable difficulty is encountered in producing a spring member possessing the requisite tension and flexibility and yet be applicable to the limited space available between the margin of the lens and the shoe of the mounting and at the same time afford the necessary tension and without detracting from the appearance of the connection. It is therefore the primary object of the present invention to provide a construction in a spring mounting of the type above referred to embodying a one piece plate spring element which is so formed as to have a multiple spring action and thereby the action of the spring is enhanced and assemblage thereof is facilitated.

A further object is to provide a construction in the plate spring element whereby on clamping the element under pressure between its supporting shoe and the margin of a lens dual thrusts will be imposed on the free end or ends of the spring in a fashion to augment the tension thereof so as to insure against a loose connection between the parts and also maintain the fastening screw tight in the straps.

With the foregoing objects in view, together with such other objects and advantages as may subsequently appear, the invention is carried into effect as illustrated on an exaggerated scale in the accompanying drawing, in which:

Fig. 1 is a view in elevation of a rimless eyeglass lens showing the invention as applied both to the temple attachment and to the bridge piece and depicting a preferred embodiment of the invention;

Fig. 2 is a view of the temple attachment as seen partly in section;

Fig. 3 is a view in section and elevation as seen on the line 3—3 of Fig. 2 in the direction indicated by the arrows;

Fig. 4 is a detail of the bridge piece connection partly in section;

Fig. 5 is a view in section as seen on the line 5—5 of Fig. 4 in the direction indicated by the arrows;

Fig. 6 is a view partly in elevation of the mounting shown in Fig. 4 with parts separated and in a partially assembled position and showing the spring element in its normal position;

Fig. 7 is a perspective view of a modified form 10 of the spring element employed in the mounting shown in Figs. 4 and 6.

Referring to the drawing more specifically, A indicates an eyeglass lens of conventional construction, B designates a temple mounting, and 15 C denotes a bridge piece mounting, which mountings are attached to the lens A in a usual fashion.

Each of said mountings embodies a shoe 10 connecting a pair of straps 11 positioned astride the rim portion of the lens; the straps 11 being connected together on opposite sides of the lens by a screw 12 which passes through an opening 13 in the lens in the conventional manner; the opening 13 being slightly larger in diameter than the shank of the screw to afford a clearance 20 therebetween and the screw being passed through one of the straps and screwed into engagement with the other in the well known manner. The shoe 10 is spaced throughout from the margin of the lens except when applied to the temple 25 mounting in which case one end 14 of the shoe is turned to abut the edge of the lens. By preference the face of the shoe presented toward the edge of the lens is straight and flat throughout except as to the end portion of the shoe that 30 abuts the lens in the temple mounting. The straps 11 lead from opposed portions of the shoe intermediate the ends thereof so that the end portions of the shoe protrude beyond the side margins of the strap in overlying relation to the 35 margin of the lens.

The essence of the invention resides in a plate spring D interposed between the margin of the lens A and the inner face of the shoe 10 which spring is bowed and is affixed to the intermediate 45 portion of the shoe by means of a rivet 15 with its outer convex face presented to the shoe; the spring being held against turning on the shoe by pairs of lugs 16 projecting from opposite sides thereof and protruding astride the straps 11 as 50 particularly shown in Fig. 3.

In carrying out the invention as shown in Figs. 1 to 7 inclusive, a knob-like protrusion 17 is formed on the outer arcuate face of the spring adjacent the free end or ends thereof, against which an 55

- outer end portion of the shoe is adapted to abut on compressing the spring between the shoe and the margin of the lens, in such manner as to impart an augmented thrust on the outer end portion of the spring relative to the tension imparted to the spring by flexion under the opposed pressures imposed thereon on initially advancing the shoe toward the margin of the lens when the tip or tips of the spring are brought into contact with the latter, which latter action tends to straighten the bow of the spring by inward movement of the portion thereof attached to the shoe relative to the end portion or portions that abut the lens.
- 15 The protrusion 17 may be formed on the spring in any suitable manner as by forming an indent in the spring from the concave side thereof to form the knob-like projection on the outer convex face of the spring as shown in Fig. 5, or by 20 pressing an extruded loop from the material of the spring to protrude from the outer convex face thereof as shown in Fig. 7. Protrusions of this character have little or no flexibility relative to the main body of the spring and will not 25 flatten out or weaken and accordingly will continue to exert a maximum of forward thrust at all times.

From the foregoing it will be seen that I have provided a spring for eyeglass lens mountings 30 that while having a multiple spring action comprises a single unit that may be readily assembled in the mounting and securely held in place thereon, and which when in use will act to hold the fastening screw 12 tightly against the margin 35 of the opening 13 in the lens against unscrewing and at the same time will afford the requisite cushioned movement of the lens and shoe relative to each other.

I claim:

- 40 1. In a lens mounting for eyeglasses embodying a shoe, a pair of straps on said shoe adapted to be positioned astride a lens, and a screw connecting said straps through the lens; a bowed plate spring interposed between the margin of

said lens and the inner face of said shoe extending longitudinally thereof with at least one end of the spring seating on the margin of the lens and with an intermediate portion attached to said shoe, and a knob-like projection on a free 5 end portion of said spring abutting against the shoe when the spring is compressed between the lens edge and the shoe and adapted to act on compressing said spring between said shoe and lens to augment outward thrust of said spring 10 against said shoe.

2. In a lens mounting for eyeglasses embodying a shoe, a pair of straps on said shoe adapted to be positioned astride a lens, and a screw connecting said straps through the lens; a bowed 15 plate spring interposed between the margin of said lens and the inner face of said shoe extending longitudinally thereof with at least one end of the spring seating on the margin of the lens and with an intermediate portion attached to 20 said shoe, and an indent forming a knob-like protrusion on a free end portion of said spring arranged for abutment against the inner face of said shoe on compressing said spring between said shoe and lens to augment outward thrust 25 of said spring against said shoe.

3. In a lens mounting for eyeglasses embodying a shoe, a pair of straps on said shoe adapted to be positioned astride a lens, and a screw connecting said straps through the lens; a bowed 30 plate spring interposed between the margin of said lens and the inner face of said shoe extending longitudinally thereof with at least one end of the spring seating on the margin of the lens and with an intermediate portion attached 35 to said shoe, and an extruded loop on a free end portion of said spring abutting against the shoe when the spring is compressed between the lens edge and shoe and adapted to act on compressing said spring between said shoe and lens to augment outward thrust of said spring against said 40 shoe.

ROBERT SUMNER.
